INVENTOR
GEORGE ASHTON

BY *James V. Ramsey*
ATTORNEY

UNITED STATES PATENT OFFICE.

GEORGE ASHTON, OF CINCINNATI, OHIO, ASSIGNOR TO THE CENTRAL FROG AND SWITCH COMPANY, OF CINCINNATI, OHIO, A CORPORATION OF OHIO.

RAIL FASTENER.

Application filed April 13, 1922. Serial No. 554,401.

To all whom it may concern:

Be it known that I, GEORGE ASHTON, a citizen of the United States, residing at Cincinnati, in the county of Hamilton and State 5 of Ohio, have invented certain new and useful Improvements in Rail Fasteners, of which the following is a specification.

My invention relates to fasteners for securing rails to metallic ties.

10 The objects of my invention are to provide simple, economical, efficient and easily operated means for securing rails to metallic ties and of conveniently removing them therefrom when desired.

15 My invention consists in the novel construction, combination and arrangement of parts as herein set forth and claimed.

In the drawings:

Fig. 1 is a perspective view of a metallic tie and a portion of two rails shown in dotted lines in position thereon with two of my novel fasteners or clamping members in open position for placing or removing the rail and two of said fasteners 25 in rail holding position;

Fig. 2 is a side elevation of my improved fasteners mounted on a metallic tie in engagement with the rails, the tie being shown in section;

30 Fig. 3 is a plan view of Fig. 2 with the ball of the rails partly broken away to show my invention and its relation to the web of the rails;

Fig. 4 is a perspective view of the preferred fastener before being secured in holding position;

Fig. 5 is a vertical section through Fig. 4;

Fig. 6 is an elevational view of the rivet used for the preferred fastener;

40 Fig. 7 is a side elevation of a modified construction of fastener before the fastening lug has been bent to holding position;

Fig. 8 is a perspective view thereof; and

Fig. 9 is a vertical section through Fig. 7.

45 My invention is used in connection with metallic ties or tie plates 1 having downwardly extending side flanges 2 and preferably a downwardly extending longitudinal rib 3 forming spaces 4 and 5 between said flanges and rib. The tie is also provided with suitable rivet holes 6 upon each side of the flanges 7 and 8 of the rail 9 which latter, has the usual vertical web 10 and ball 11.

55 In the embodiment of my invention as

illustrated and which shows preferred constructions, I provide a fastener consisting of a head 12 having a hole 13 extending vertically therethrough with a rail engaging lug 14 extending laterally therefrom and cut 60 away upon its lower surface at an angle to its upper surface to conform to the shape of the flange of the rail and permit it to fit thereover and having its free end formed eccentric to its length with one side curved 65 at 15 and formed flat or straight at 16. Said fastener is also provided with a fastening lug 17 extending laterally from said head substantially at right angles to said rail engaging lug 14 and adapted to be bent downwardly 70 into holding engagement with the side of the tie.

The fastening devices are permanently pivoted to the tie by rivets 18 each having a head 19 and stem 20 extending through 75 holes in the tie and secured therein by riveting heads 21 thereon.

My invention is capable of some modification without departure from its scope or spirit as defined in the claims, as for instance, the fastening device may consist of a single piece, as shown in Figs. 7, 8 and 9, comprising a head 22, pivot stem 23, rail engaging lug 14 and fastening lug 17. Each tie between the joints of the rails is provided 80 near each end with two fasteners as shown in Fig. 1 and at the joints it is provided with four fasteners as shown in Figs. 2 and 3.

When it is desired to use my invention 90 the fasteners are secured to each end of the rails as above described. The ties are placed in position with the fasteners turned to the position shown at the right in Fig. 1. The rails are then placed upon the ties and the 95 fasteners turned to the position shown at the left in Fig. 1. The rail fastening lugs 17 are then bent downwardly against the sides of the tie as shown in Figs. 2 and 3 thereby securely holding the rail engaging 100 lugs in contact with the webs of the rails and preventing the fastening device from turning.

To remove a rail simply bend the fastening lugs upwardly to their original position 105 by driving against the sides 25 (see Fig. 3) which forces or bends said lugs upwardly into horizontal position as shown in Fig. 4 thereby permitting the fasteners to be turned on the rivets 18 thus bringing the 110

flat ends 16 out of engagement with the web 10 and turning the fasteners to the position shown at the right in Fig. 1 whereupon the rail may be readily removed from the ties 5 and another rail substituted therefor and secured to the ties the same as in the first instance.

The edges of rail flanges as ordinarily constructed frequently have a rough or uneven 10 surface and an advantage of my invention is that my rail fastener does not come in contact with such edges but rests upon the upper surface of the flange and bears against the smooth surface of the web so that it is 15 adapted to form a proper holding engagement with any rail which it is desired to fasten.

Another advantage of my invention is that the fastener may be used with rails 20 having flanges of varying widths. Another advantage is that the rail engaging lug has a surface partly flat and partly curved or 25 eccentric whereby the fastener may be turned upon its pivot into firm holding engagement with the web of the rail thereby preventing rattling, tipping laterally or longitudinal creeping of the rail.

What I claim as new and desire to secure by Letters Patent is:

- 30 1. In combination with a metallic tie and the rail thereon, a clamping member pivotally connected to said tie and provided with a head having a rail engaging lug adapted to extend over the flange of the rail and having a fastening lug adapted to be bent down against the side or edge of the tie.
2. In combination with a metallic tie and the rail thereon, clamping members pivotally connected to said tie and frictionally 40 engaging said rail, said clamping members each having a head provided with a lug on one side thereof adapted to be bent downwardly against the tie thereby securely holding said head tightly against said web.
- 45 3. In combination with a metallic tie and the rail thereon, a clamping member connected to said tie and provided with a head

adapted to extend over the flange of the rail and having a lug adapted to be bent down against a corner of the tie, substantially as 50 set forth and for the purposes specified.

4. In combination with a metallic tie having a hole therein and a rail thereon, a clamping member having a projecting head adapted to engage the flange and web of 55 the rail and having a hole therethrough, a rivet extending through the hole in said head and said tie and riveted to said tie, and a lug on said clamping member adapted to be bent downwardly into holding engagement with said tie, substantially as set forth and for the purposes specified.

5. In a device of the class described, a rail fastener comprising a head having a lug thereon to engage the flange and web of 65 the rail and having a lug adapted to be bent into holding engagement with the tie and means for pivotally attaching said device to the tie.

6. In combination with a metallic tie and the rail thereon, a clamping member pivotally connected to said tie and having a head adapted to engage the flange and web of the rail and a lug adapted to be bent into holding 70 engagement with the tie.

7. In combination with a metallic tie and the rail thereon, a clamping member pivotally connected to said tie and provided with a lug having its free end partly curved or eccentric and partly straight to permit said 80 lug to be turned into firm holding engagement with the web of the rail and having a laterally extending lug adapted to be bent into holding engagement with the tie.

8. In combination with a metallic tie and the rail thereon, clamping members each pivotally connected to said tie and each having a lug engaging the web of said rail and a lug adapted to be bent into holding engagement with the tie whereby the rail is 85 firmly held and prevented from rattling, tipping laterally or creeping longitudinally.

GEORGE ASHTON.
